UNITED STATES PATENT OFFICE.

THOMAS COLDWELL AND WILLIAM H. COLDWELL, OF NEWBURG,
NEW YORK.

AWNING.

SPECIFICATION forming part of Letters Patent No. 586,131, dated March 19, 1895.

Application filed January 10, 1895. Serial No. 534,443. (No model.)

To all whom it may concern:

Be it known that we, THOMAS COLDWELL and WILLIAM H. COLDWELL, citizens of the United States, residing at Newburg, in the county of Orange and State of New York, have invented certain new and useful Improvements in Awnings; and we do hereby declare the following to be a full, clear, and exact description of the invention, such as will enable others skilled in the art to which it appertains to make and use the same.

Our invention is an improvement in lawn awnings for lawn seats and the like and consists in the novel features of construction hereinafter described reference being had to the accompanying drawings which illustrate several forms in which we have contemplated embodying our invention.

Referring to the said drawings, Figure 1 represents a side elevation of a lawn seat with our awning applied thereto. Fig. 2 is a similar view of the awning showing it in a different position, the seat being taken away. Fig. 3 is a view similar to Fig. 2 showing the awning in position to shade the back of the occupants. Fig. 4 is a front view of the settee and awning, the front portion of the awning being cut away as indicated by the part shown in section. Figs. 5 and 6 are detail views illustrating the manner of constructing the settee. Figs. 7, 8 and 9 are views similar to Figs. 1, 2 and 3 showing a slightly modified form of awning frame. Fig. 10 is a view similar to Fig. 1 showing still another slightly modified form of awning frame.

In the form shown in Figs. 1 to 6 inclusive, A A represent the two end frames of the settee formed of cast iron and having the seat and back portions provided with lateral flanges a as shown which form a broad surface to receive the slats B B of the seat and back. The broad seat and back portions of the end frames are provided with tapering dovetailed lugs a' a' as indicated in Figs. 4 and 5 which are engaged by tapering dovetailed recesses b in the slats (see Fig. 6) thereby locking the parts of the settee rigidly together without the use of stays, braces or any other devices for connecting the end frames.

It will thus be seen that the settee can be very readily taken apart and set up and can

be very cheaply made and conveniently transported.

The frame of the awning is supported by two upright standards C C which are preferably bolted to the end frames A A of the settee (as shown in Figs. 1, 2 and 3) so that they can be attached to and detached from the same very readily. The standards C C are connected at the top by a cross bar C³. A link c is pivoted to each of the standards C C adjacent to their upper ends and to each link two end bars c' c² are pivoted, extending forward and backward respectively as shown in the drawings. The end bars c' c² are connected at their outer ends by a cross bar C' similar to the cross bar C³, and the end bars c² c² are connected in a similar manner by a cross bar C².

It will be seen that the cross bars C', C² and C³ are parallel and the awning strip D is secured to the cross bar C² at one end and to the bar C' at the other end, passing loosely over the top of cross bar C³. We prefer to attach the awning strip D in such a manner to cross bars C' and C² that the ends of the strip will hang down in the form of a fringe, or scalloped edge as shown in Fig. 4.

The end bars c² c² are provided with a series of notches or recesses c³ which are adapted to engage a stud or pin c⁴ on each of the standards C C to adjust the awning to different positions. In Fig. 1 we have shown the pins or studs c⁴ in the first notches of end bars c² c² and the awning in a horizontal position. In Fig. 2 the pins c⁴ are shown in the last notches of said arms and the awning arranged to extend over the front of the seat, and in Fig. 3 the awning is shown arranged to shade the back of persons occupying the settee. As the cross bars C', C² are moved to adjust the awning, the awning strip slides over the cross bar C³.

The front cross bar C' of the awning frame is preferably made slightly heavier than the rear cross bar C² so that the awning will remain in any position to which it is adjusted, as the weight of cross bar C² will hold the notched bars c² c² in engagement with the pins c⁴ c⁴.

In Figs. 7, 8 and 9 we have shown a slightly modified form of awning frame in which we

employ a single horizontal end bar c^5 at each end of the frame to connect the front and rear cross bars C^4 C^5 to which the awning strip D' is attached instead of a jointed end bar as before described. These end bars c^5 are notched as shown and engage the pins c^6 in the vertical standards C^6 , the canvas sliding over the top cross bar C^7 as the frame is adjusted. It will be seen by reference to these figures that we can obtain all of the adjustments which can be obtained with the form of frame shown in Figs. 1 to 6 inclusive. The front cross bar C^4 being heavier than the rear cross bar C^5 , the notches in the bars c^5 will be held in engagement with the pins c^6 in any position to which the frame is adjusted.

In Fig. 10 we have shown another slight modification of our device in which straight end bars c^7 are employed to connect the front cross bar C^8 and rear cross bar C^9 , notched to engage pins c^{10} in the vertical standards C^{10} as in the form just described. In this case however in order to relieve the canvas strip D^2 from strain, links c^8 are employed connecting the central portions of horizontal end bars c^7 to the upper ends of standards C^{10} just below the upper cross bar C^{11} . This construction we also find very convenient and desirable. The cross bar C^3 is made heavier than cross bar C^9 in this case also for the reason previously mentioned in describing the other forms.

While we may make the front cross bar heavier than the rear cross bar, this is not essential as the frictional contact of the awning on the central supporting bar, and the leverage afforded the front bar in most of its positions fully suffice to hold the notched bars in engagement with the pins.

What we claim, and desire to secure by Letters Patent, is—

1. The combination with the vertical standards and the central supporting bar, of an awning strip passing loosely over said central bar, movable cross bars secured to the ends of the said awning strip, end bars connecting

the ends of said cross bars and means for adjusting said end bars in respect to said standards, substantially as described.

2. The combination with the vertical standards and central supporting bar, of the movable cross bars on either side of said central bar, the end bars connecting the said movable bars at each end of the awning having notched portions, an awning strip secured to said movable cross bars and passing over said central bar, and pins in said vertical standards adapted to be engaged by the notched portions of said end bars to adjust said end bars longitudinally of the same with respect to said standards, substantially as described.

3. The combination with the vertical standards and central supporting bar connecting the upper ends of said standards of the movable cross bars, an awning strip secured thereto and passing loosely over the central bar, end bars connecting said cross bars and provided with notches or recesses, pins on said standards adapted to be engaged by said notches, one of said movable bars being of greater weight than the other, for holding said notched end bars in engagement with said pins, substantially as described.

4. The combination with the vertical standards and the central supporting bar connecting their upper ends, of the movable cross bars, an awning strip rigidly connected thereto and passing loosely over the central bar, end bars connecting said movable cross bars and provided with notches, pins on said standards adapted to be engaged by said notched end bars, and links pivotally connected to said standards and to said end bars intermediate the ends of the same, substantially as described.

In testimony whereof we affix our signatures in presence of two witnesses.

THOMAS COLDWELL.

WILLIAM H. COLDWELL.
